CLAIM

The ornamental design for a solid cosmetic, as shown and described.

DESCRIPTION

FIG. 1 is a front view of a solid cosmetic showing my new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a top perspective view thereof;

FIG. 8 is a bottom perspective view thereof;

FIG. 9 is an enlarged left side view thereof;

FIG. 10 is an enlarged view of portion "10" shown in FIG.
3;

FIG. 11 is an enlarged view of portion "11" shown in FIG.
7;

FIG. 12 is an enlarged view of portion "12" shown in FIG.
8; and,

FIG. 13 is a perspective view thereof, shown in an environment of use.

In FIGS. 1-12 the evenly spaced broken lines illustrate portions of the solid cosmetic and form no part of the claimed design. In FIG. 13 the evenly spaced broken lines illustrate environmental subject matter and form no part of the claimed design. The dash-dot broken lines illustrate a boundary to the claimed design and form no part thereof.

1 Claim, 13 Drawing Sheets
